METHOD FOR THE PREPARATION OF ALPHA NAPHTHOSELENAZOLES

Edmund B. Middleton, Woodbridge, and George A. Dawson, Stelton, N. J., assignors, by mesne assignments, to E. I. du Pont de Nemours & Company, Wilmington, Del., a corporation of Delaware

No Drawing. Application June 3, 1940,
Serial No. 338,556

7 Claims. (Cl. 260—298)

This invention relates to alpha naphthoselenazoles, more particularly 2-hydrocarbon alpha naphthoselenazole, and a method for the preparation thereof.

This application is a continuation-in-part of our copending application Serial No. 78,734, filed May 8, 1936.

Among the objects of the invention are the manufacture of alpha naphthoselenazoles, more particularly 2-hydrocarbon alpha naphthoselenazoles of high purity in good yields by a series of reactions which proceed rather smoothly with a minimum of side reactions and at an economical cost. These objects have not heretofore been obtained.

The alpha naphthoselenazoles, and especially the 2-alkyl alpha naphthoselenazoles, are very difficult compounds to produce. One method heretofore proposed for making them involves starting with alpha naphthylamine, nitrating, diazotizing and subsequently replacing the diazo group. This method does not give satisfactory results.

In accordance with the present invention a 2-hydrocarbon alpha naphthoselenazole is produced from a beta naphthylamine as the starting material. Generally stated, this is accomplished by the following series of reactions: (1) treating a beta naphthylamine in the form of a salt with a selenocyanate in the presence of an oxidizing agent; (2) heating the resultant product with a strong hydrolysing agent; and (3) treating the hydrolysis product with an acylating agent. The final product may be recovered in any convenient manner.

The series of reactions in question starting with beta naphthylamine may be carried out in several different ways, as follows:

A. The beta naphthylamine is converted in a well known manner to a 1-halogeno-2-amino naphthalene salt. The amine salt of the 1-halogeno-2-amino naphthalene is then reacted with a selenocyanate, preferably an alkali metal selenocyanate such as potassium selenocyanate. The reaction product is preferably made alkaline with ammonia. The resultant product is then hydrolysed, preferably by treatment with a strong alkaline solution such as a solution of sodium hydroxide or potassium hydroxide. The resultant product obtained upon hydrolysis is then preferably oxidized, for example, by treatment with a dilute hydrogen peroxide solution. The oxidation product is preferably separated. It is then reduced and reacted with an acylating agent. This may be accomplished, for example, by carrying out the reaction with acetic anhydride in the presence of metallic zinc, thereby producing a 2-methyl alpha naphthoselenazole.

B. The beta naphthylamine and a selenocyanate in a suitable solvent are treated with a

free halogen. A suitable solvent for this purpose should preferably be substantially inert to the free halogen. The solvent employed should also preferably be a solvent for both the beta naphthylamine and the selenocyanate, although this is not absolutely essential. It should preferably be non-acid since acid solvents precipitate selenium from certain selenocyanate compounds. It is ordinarily preferable to employ a mixture of solvents because it has been found that in most instances one solvent does not give the desired results. Alcohols, such as, for example, ethyl alcohol, are common solvents for both beta naphthylamine and selenocyanates such as the alkali metal selenocyanates. These alcohols, however, are halogenated by free halogens such as bromine. This halogenation may be substantially avoided by employing a mixture of solvents such as, for example, a mixture of an alcohol and a non-acid solvent substantially inert to halogen. Mention may be made particularly of mixtures of alcohol with halogenated hydrocarbons, e. g. chloroform and/or carbon tetrachloride.

The product obtained is preferably treated with ammonia. The resultant product is then hydrolysed with a strong alkaline solution. It may be isolated from the alkaline solution by oxidation. The product thus obtained is then reduced and reacted with an acylating agent to produce a 2-hydrocarbon alpha naphthoselenazole.

C. The beta naphthylamine is reacted directly with cupric selenocyanate in the presence of a solvent. The reaction product is extracted as a salt by treatment with a mineral acid. Treating the salt solution with ammonia precipitates the free base. The resultant product is then hydrolysed and the hydrolysis product is preferably isolated by oxidation, for example, with hydrogen peroxide. The product thus isolated is then reduced and reacted with an acylating agent to produce a 2-hydrocarbon alpha naphthoselenazole.

The 2-hydrocarbon alpha naphthoselenazoles thus produced have the following general formula:

in which R represents a naphthalene nucleus, Se represents a selenium atom attached to an alpha position of said naphthalene nucleus, N represents a nitrogen atom attached to an adjoining beta position of said naphthalene nucleus, C represents a carbon atom between said selenium atom and said nitrogen atom, and R₁ represents hydrogen or a hydrocarbon group, for example, an alkyl group, as methyl, ethyl, propyl, or the like; 55 aryl, as, phenyl, tolyl, xylyl, naphthyl, diphenyl, 60 aryl, as, phenyl, tolyl, xylyl, naphthyl, diphenyl,

or the like; aryl alkyl, as, benzyl, cinnamyl. The nature of the hydrocarbon group will depend upon the particular acylating agent employed in carrying out the reactions described. For instance, in order to produce a 2-methyl alpha naphtho-selenazole, acetic anhydride is used, or acetyl chloride. To produce a 2-ethyl alpha naphtho-selenazole, propionic anhydride or propionyl chloride is used. In order to produce 2-hydrocarbon alpha naphthoselenazoles having a greater or 10 lesser number of carbon atoms, an acylating agent is employed appropriate to the number of carbon atoms desired. For instance, the lauryl derivative may be produced by using lauroyl chloride as the acylating agent. The phenyl derivative may be produced by using benzoyl chloride as the acylating agent, and the cinnamyl derivative may be produced by employing cinnamoyl chloride as the acylating agent. Similarly other acylating agents of the type described are employed to produce other alpha naphthoselenazoles. The radical R¹ may contain substituent groups. Among such groups are, for example, halogen (e. g. chlorine, bromine, iodine, fluorine), alkyl (e. g. methyl, ethyl, propyl, butyl and higher homologues) and alkoxy (e. g. methoxy, ethoxy and higher homologues). It is essential, however, for the purpose of the present invention that the starting material be a beta-naphthylamine in which the alpha position which is eventually to be linked to a selenium atom be either unoccupied or occupied by a halogen atom. The beta position will naturally be occupied by an amino group. It has been found that by using these starting materials and proceeding in the manner described difficulties are avoided which ordinarily are encountered in other proposed processes such as those involving the use of alpha naphthylamine as a starting material followed by nitration, diazotization, etc.

The compounds given in Formula 1 are referred to herein as the 2-hydrocarbon alpha naphthoselenazole bases. These bases react with organic esters of organic and inorganic acids to form quaternary ammonium salts. Among the esters which may be reacted with these bases in order to produce such quaternary ammonium salts are, for example, methyl chloride, ethyl chloride and higher alkyl homologues, methyl bromide, ethyl bromide, propyl bromide and higher alkyl homologues, ethyl paratoluene sulfonate, dimethyl sulfate, diethyl sulfate and the corresponding chlorates and nitrates.

The 2-alkyl substituted quaternary salts produced in the manner described are useful as intermediates in the manufacture of dyestuffs. They may be used, for example, in making cyanine dyes, pseudocyanine dyes, carbocyanine dyes, dicarbocyanine dyes and other types of dyes. Many of these dyes are useful in making photographic emulsions, particularly as sensitizers in such emulsions. The carbocyanine dyes are especially valuable as green-blind red sensitizers, that is to say, they sensitize in the red region of the spectrum but for photographic purposes are substantially insensitive in the green region of the spectrum.

The invention will be further illustrated but is not limited by the following examples in which the quantities are stated in parts by weight.

Example I

A solution of 51 parts of the hydrochloride of 1-bromo-2-aminonaphthalene in about 70 parts

of alcohol was treated with 28 parts of potassium selenocyanate in 80 parts of water. After standing over night at room temperature, the mixture was evaporated to dryness and extracted many times with hot water. The extract was made alkaline with ammonia and the aminonaphtho-selenazole precipitated. It was recrystallized from alcohol. Yield 36 parts; M. P. 252° C. This compound has the formula:

A mixture of 28 parts of the aminonaphtho-selenazole, 28 parts of sodium hydroxide and 50 parts of water was heated together in a nickel crucible for three hours on an electric hot plate. The cover of the crucible was adjusted so that steam could escape. Water lost by evaporation was replaced as it boiled off. Finally the crucible was evaporated to dryness and heated until the fumes due to decomposition began to appear. The residue was taken up with water and filtered. The filtrate was cooled, and dilute hydrogen peroxide added drop by drop until no more precipitation formed. The precipitated diselenide, a yellow amorphous powder, was separated by filtration, washed and dried. A yield of 13 parts was obtained. This compound has the formula:

This was heated to boiling in 108 parts of acetic anhydride under a reflux condenser and 4 parts of zinc gradually added. Heating was continued for thirty minutes. The hot solution was filtered from some unreacted zinc, and poured into water. The solution was later extracted with ether, and after drying the ether solution and removing the ether by evaporation, needle crystals of the 2-methyl-alpha-naphthoselenazole were obtained. It melted at 81°-82° C. Yield 7 parts.

On heating the crude material with three times the calculated quantity of ethyl iodide under reflux for twenty-four hours and then evaporating the excess ethyl iodide, the 2-methyl-alpha-naphthoselenazole ethiodide remained as a crystalline solid. It was crystallized from alcohol, whereby it was obtained as small needle crystals, 60 of pale yellow color.

Example II

Twenty-five (25) parts of beta-naphthylamine in 315 parts of glacial acetic acid, were treated with 47.8 parts of cupric selenocyanate. After heating under a reflux condenser for fifteen minutes about 30 parts of 33% HCl were added and the heating was continued for fifteen minutes longer. The solution was filtered hot and the residue washed well with hot water. The combined filtrates were neutralized with ammonia and the aminonaphthoselenazole precipitated. The overall yield was substantially lower than in Example I. The compound was converted to methyl-naphthoselenazole as in Example I.

Example III

Twenty-five (25) parts of beta-naphthylamine and 13.8 parts of potassium selenocyanate were dissolved in about 80 parts of alcohol, in a 3-necked flask, equipped with a stirrer. The temperature was kept below 25° C. while a solution of 28 parts of bromine in about 45 parts of chloroform was added drop by drop. The flask was then allowed to stand at room temperature for several hours, after which it was brought to a boil for a minute and then allowed to stand at room temperature for twelve hours. The solution was diluted with several volumes of cold water and an oil separated which on standing deposited cream colored crystals. These were filtered and recrystallized from alcohol, about 7.5 parts of product being obtained. This product was the hydrobromide of 2-amino alpha naphthoselenazole melting around 281°-283° C. The free base was liberated by treating with ammonia. The resultant base was then converted to 2-methyl alpha naphthoselenazole, as described in Example I.

Example IV

A carbocyanine dye was obtained as follows: One (1) part of the ethiodide made as described in Example I and 6 parts of dry pyridine and about 1 part of ethyl orthoformate were heated under reflux for twenty minutes. An intense blue color developed. On cooling, the dye was obtained as beautiful greenish-gold crystals. This dye, sym-3:3'-diethyl-naphthoselenocarbocyanine iodide, has the structure:

It is a red sensitizer for a photographic emulsion. When dissolved in alcohol and added to a negative emulsion, it conferred extra sensitivity with maximum at approximately 665±5 m. u. and extending to 700 m. u.

In a manner similar to that described in Examples I, II and III, other 2-alkyl-naphthoselenazoles and their quaternary salts may be prepared. For instance, the naphthalene nucleus may contain non-reactive substituents, e. g. alkyl (methyl, ethyl, propyl, and higher homologues) or alkoxy radicals (methoxy, ethoxy, and higher homologues) in one or more of the 3-, 4-, 5-, 6-, 7- or 8-positions. It will be understood, of course, that the ring closing positions of the beta naphthylamine initially employed must be free of substituents. The expression "beta naphthylamine in the form of a salt" is intended to include and cover an amine salt of beta naphthylamine either as pre-formed or as formed in situ during a reaction. In carrying out the first step of the reaction using an alkali metal selenocyanate, a non-acid medium is preferably employed because it has been found that the presence of an acid causes the precipitation of selenium. It will be understood, however, that if the beta naphthylamine is present as a salt, it is substantially non-acid. The reaction between the salt of the beta naphthylamine, as, for example, a hydrohalide salt, and an alkali metal selenocyanate, as, for example, potassium selenocyanate, results in the elimination of an alkali

metal halide and in the formation of a seleno-urea which may be isolated for purification if desired. In the presence of an oxidizing agent the formation of the seleno-urea is apparently merely transitory and the product immediately obtained is a 2-amino alpha naphthoselenazole. The oxidizing agent may be a halogen atom which is already attached to the naphthylamine nucleus adjacent the amino group, as in Example I, or it may be a free halogen added contemporaneously or simultaneously, as in Example II. In either event a ring closure occurs. Other oxidizing agents may be employed in this step of the process, as, for instance, potassium ferricyanide, hydrogen peroxide, or potassium permanganate. The salt of 2-amino alpha naphthoselenazole will ordinarily separate directly and if desired may be employed directly in the second or hydrolysis step of the process. It is ordinarily preferable, however, to convert this salt to the free base by neutralization with ammonia or some other non-hydrolysing base. In carrying out the first step of the process any known selenocyanate may be used, although the alkali metal selenocyanates are preferred, e. g. sodium and potassium selenocyanates. If cupric selenocyanate is employed, it is preferable to use it in an organic solvent. For this purpose glacial acetic acid may be used, although other solvents may be employed.

In carrying out the second step of the process, any strong hydrolysing agent may be employed, for example, solutions of sodium hydroxide, potassium hydroxide or mixtures thereof. The hydrolysis action causes the selenazole ring of the 2-amino alpha naphthoselenazole to be broken, thereby forming a selenonaphthol. The selenonaphthol may be reacted directly with an acylating agent, as, for example, an acid anhydride or an acid halide of the types previously mentioned. In this event a substantial excess of acylating agent will be required in order to neutralize the alkaline hydrolysing agent which is still present. For this reason and in order to further purify the intermediate product before carrying out the final step, it is often desirable to oxidize the selenonaphthol to a diselenide, which can be separated as such and purified. This may be accomplished by hydrogen peroxide, air, oxygen, or other oxidizing agents. If the selenonaphthol is oxidized to the diselenide, the latter must be again reduced to the selenonaphthol before reaction with the acylating agent will take place. This reduction is accomplished by the use of nascent hydrogen, or any other suitable reducing agent. It may be accomplished, for example, by adding metallic zinc to an acid acylating medium. The use of an acid halide, as, for example, an acid chloride as the acylating medium is particularly desirable because it can be added directly to the hydrolysis reaction product without requiring a large excess to neutralize the alkali present. This also results in the elimination of the diselenide formation step where the purpose of this step is to eliminate the alkaline medium.

Having thus described the invention, what we claim as new and desire to secure by Letters Patent of the United States is:

1. In a method of making a 2-alkyl alpha-naphthoselenazole, the series of steps which comprises (1) reacting beta naphthylamine in an acid solvent medium with copper selenocyanate, (2) heating the reaction mixture in an acid medium, (3) neutralizing the resultant reaction mixture with ammonia and separating the precipitate, (4) heating said precipitate with a strong

alkaline hydrolysing agent; (5) treating the hydrolysis product with an oxidizing agent and separating the precipitate; (6) heating said precipitate with a lower aliphatic carboxylic acid anhydride in the presence of nascent hydrogen and separating the resultant 2-alkyl alpha naphthoselenazole:

2. In a method of making 2-methyl alpha naphthoselenazoles, the series of steps which comprises (1) reacting beta naphthylamine in glacial acetic acid with copper selenocyanate; (2) refluxing the reaction mixture with hydrochloric acid; (3) neutralizing with ammonia and separating the resultant precipitate; (4) heating said precipitate with a strong caustic alkali solution; (5) treating the resulting product with an oxidizing agent and separating the precipitate; (6) heating said precipitate with acetic anhydride in the presence of zinc and separating the resultant 2-methyl alpha naphthoselenazole.

3. In a method of making a 2-alkyl alpha naphthoselenazole, the series of steps which comprises (1) contemporaneously reacting beta naphthylamine, an alkali metal selenocyanate and a free halogen and heating the reaction mixture; (2) neutralizing and separating the precipitate; (3) heating the precipitate with a strong alkaline hydrolysing agent; (4) treating the hydrolysis product with an oxidizing agent and separating the resultant precipitate; and (5) heating said precipitate with a lower aliphatic carboxylic acid anhydride in the presence of nascent hydrogen.

4. In a method of making a 2-methyl alpha naphthoselenazole, the series of steps which comprises (1) reacting beta naphthylamine with potassium selenocyanate and while keeping the temperature below about 25° C. adding bromine; (2) thereafter heating the reaction mixture; (3) neutralizing the reaction mixture with ammonia and separating the resultant precipitate; (4) heating the separated precipitate with a strong caustic alkali hydrolysing agent in aqueous solu-

tion; (5) treating the hydrolysis product with hydrogen peroxide and separating the precipitate; (6) heating said precipitate with acetic anhydride in the presence of zinc and separating the 2-methyl alpha naphthoselenazole.

5. The method of preparing 2-alkyl-alpha-naphthoselenazoles which comprises treating a beta naphthylamine in the form of a salt with a selenocyanate under oxidizing conditions, hydrolyzing the oxidation product with an alkali, oxidizing the hydrolysis product, treating the insoluble oxidation product with an acylating agent and reducing it with nascent hydrogen.

6. In a method of making a 2-alkyl-alpha-naphthoselenazole, the series of steps which comprises treating a beta naphthylamine in the form of a salt with a metallic selenocyanate in the presence of a free halogen and in the presence of a substantially non-acid organic solvent which is substantially inert to the free halogen, to form a 2-amino-alpha-naphthoselenazole, heating the 2-amino-alpha-naphthoselenazole with a strong hydrolyzing agent, oxidizing the hydrolysis product, reducing the insoluble oxidation product with nascent hydrogen, and adding an acylating agent.

7. In a method of making a 2-alkyl-alpha-naphthoselenazole, the series of steps which comprises treating a beta naphthylamine in the form of a salt and unsubstituted in the alpha position with a metallic selenocyanate and a free halogen in a mixture of substantially non-acid organic solvents, at least one of said solvents being a common solvent for both the beta naphthylamine and the selenocyanate and another being a solvent for said free halogen and substantially inert thereto, to form a 2-amino-alpha-naphthoselenazole, heating the 2-amino-alpha-naphthoselenazole with a strong hydrolyzing agent, reducing the insoluble oxidation product with nascent hydrogen, and treating with an acylating agent.
